US0D1112143S

(12) **United States Design Patent** (10) **Patent No.:** **US D1,112,143 S**
(45) **Date of Patent:** **** Feb. 10, 2026**

(54) **DISPLAY DEVICE**

(71) Applicant: **Samsung Display Co., Ltd.**, Yongin-si (KR)

(72) Inventors: **Myeong Il Choi**, Yongin-si (KR); **Seonwoo Pyo**, Yongin-si (KR); **Juyeon Baek**, Yongin-si (KR); **Woo Won Lee**, Yongin-si (KR)

(73) Assignee: **Samsung Display Co., Ltd.**, Yongin-si (KR)

(**) Term: **15 Years**

(21) Appl. No.: **29/936,053**

(22) Filed: **Apr. 5, 2024**

(30) **Foreign Application Priority Data**

Oct. 6, 2023 (KR) 30-2023-0039232

(57) **CLAIM**

The ornamental design for a display device, as shown and described.

DESCRIPTION

FIG. 1 is a perspective view of the display device in an unfolded state.

FIG. 2 is a front view thereof,

FIG. 3 is a rear view thereof,

FIG. 4 is a left-side view thereof,

FIG. 5 is a right-side view thereof,

FIG. 6 is a top view thereof,

FIG. 7 is a bottom view thereof;

FIG. 8 is a perspective view of the display device in a folded state,

FIG. 9 is a front view thereof,

FIG. 10 is a rear view thereof,

FIG. 11 is a left-side view thereof,

FIG. 12 is a right-side view thereof,

FIG. 13 is a top view thereof; and,

FIG. 14 is a bottom view thereof.

The broken lines in the drawings represent portions of the display device that form no part of the claimed design.

1 Claim, 14 Drawing Sheets
